(57) **CLAIM**

The ornamental design for a flashlight, as shown and described.

DESCRIPTION

FIG. 1 is a top plan view of a flashlight according to a first embodiment of the invention.

FIG. 2 is a right side elevational view of the flashlight according to the first embodiment of the invention.

FIG. 3 is a left side elevational view of the flashlight according to the first embodiment of the invention.

FIG. 4 is a bottom plan view of the flashlight according to the first embodiment of the invention.

FIG. 5 is a front elevational view of the flashlight according to the first and second embodiments of the invention.

FIG. 6 is a rear elevational view of the flashlight according to the first and second embodiments of the invention.

FIG. 7 is a top plan view of a flashlight according to a second embodiment of the invention.

FIG. 8 is a right side elevational view of the flashlight according to the second embodiment of the invention.

FIG. 9 is a left side elevational view of the flashlight according to the second embodiment of the invention.

FIG. 10 is a bottom plan view of the flashlight according to the second embodiment of the invention.

FIG. 11 is a top plan view of a flashlight according to a third embodiment of the invention.

FIG. 12 is a right side elevational view of the flashlight according to the third embodiment of the invention.

FIG. 13 is a left side elevational view of the flashlight according to the third embodiment of the invention.

FIG. 14 is a bottom plan view of the flashlight according to the third embodiment of the invention.

FIG. 15 is a front elevational view of the flashlight according to the third and fourth embodiments of the invention.

FIG. 16 is a rear elevational view of the flashlight according to the third and fourth embodiments of the invention.

FIG. 17 is a top plan view of a flashlight according to a fourth embodiment of the invention.

FIG. 18 is a right side elevational view of the flashlight according to the fourth embodiment of the invention.

FIG. 19 is a left side elevational view of the flashlight according to the fourth embodiment of the invention; and,

FIG. 20 is a bottom plan view of the flashlight according to the fourth embodiment of the invention.
